VALVE

Lloyd F. Bender, Hayward, Wis. 54843

Filed Aug. 20, 1971, Ser. No. 173,724

Term of patent 14 years

Int. Cl. D23—01

U.S. Cl. D23—19

Fig. 3

Fig. 1

Fig. 4

Fig. 2

Fig. 5

FIG. 1 is a perspective view of a valve showing my new design;

FIG. 2 is an enlarged side elevational view thereof;

FIG. 3 is a top plan view thereof;

FIG. 4 is another side elevational view taken at a right angle to the side shown in FIG. 2; and

FIG. 5 is a bottom view thereof.

I claim:

The ornamental design for a valve, substantially as shown.
